The ornamental design for a wall plate, as shown and described.

DESCRIPTION

The present application is related to U.S. Pat. No. D473,447, issued Apr. 22, 2003, included by reference herein.

The present application is related to U.S. Pat. No. D506,382, issued Jul. 21, 2005, included by reference herein.

The present application is related to U.S. Pat. No. D633,776, issued Mar. 8, 2011, included by reference herein.

The present application is related to U.S. Pat. No. D405,995, issued Feb. 23, 1999, included by reference herein.

The present application is related to U.S. Pat. No. D522,353, issued Jun. 6, 2006, included by reference herein.

The present application is related to U.S. Pat. No. D305,863, issued Feb. 6, 1990, included by reference herein.

FIG. 1 is a front elevational view of a wall plate according to my new design;

FIG. 2 is a rear elevational view thereof;

FIG. 3 is a side elevational view thereof, the opposite side being a mirror image thereof;

FIG. 4 is a top plan view thereof, the bottom plan view being a mirror image thereof;

FIG. 5 is a sectional view thereof, taken along lines 5-5 as indicated in FIG. 1; and,

FIG. 6 is a second sectional view, taken along lines 6-6 as indicated in FIG. 1.
